UNITED STATES PATENT OFFICE

136,436

DESIGN FOR A PLUG CLOSURE FOR BARRELS, CANS, OR THE LIKE

Glenn T. Rieke, Auburn, Ind.

Application June 25, 1943, Serial No. 110,529

Term of patent 14 years

To all whom it may concern:

Be it known that I, Glenn T. Rieke, a citizen of the United States, residing at Auburn, in the county of De Kalb and State of Indiana, have invented a new, original, and ornamental Design for a Plug Closure for Barrels, Cans, or the like, of which the following is a specification, reference being had to the accompanying drawing, forming a part thereof.

In the drawing Fig. 1 is a perspective top view of a plug closure for barrels, cans, or the like showing my new design, and Fig. 2 is a perspective bottom view of such design.

I claim:

The ornamental design for a plug closure for barrels, cans, or the like, as shown.

GLENN T. RIEKE.
